Primary Examiner—Dominic Simone

(57) CLAIM

The ornamental design for a Santa Claus foot, as shown.

DESCRIPTION

FIG. 1 is a right side view.

FIG. 2 is a left side view.

FIG. 3 is a front view.

FIG. 4 is a rear view; and,

FIG. 5 is a bottom view.

The top view is unornamented. It is therefore unclaimed and not shown.
